(57) **CLAIM**

The ornamental design for a hernia belt, as shown and described.

DESCRIPTION

FIG. 1 is a top, front perspective view of a hernia belt embodying our new design;

FIG. 2 is a top view thereof;

FIG. 3 is a bottom view thereof;

FIG. 4 is a side view thereof as seen from the right-hand side of FIG. 2;

FIG. 5 is a side view thereof as seen from the left-hand side of FIG. 2;

FIG. 6 is a rear view thereof; and,

FIG. 7 is a front view thereof.

Portions of the hernia belt shown in phantom lines in FIGS. 1-7 form no part of the claimed design.

1 Claim, 3 Drawing Sheets

US D863,565 S
